LIGHTER

George Philip Schmitt, New York, N. Y., assignor
to Platinum Products Corporation, a corpora-
tion of New Jersey

Application November 17, 1933, Serial No. 698,402

6 Claims. (Cl. 67—7)

This invention relates to lighters of the character employing a catalytic igniting element, for use with cigarettes and the like, and my improvement is directed to novel, simple and inexpensive means for supporting the catalytic element, in the form of a disk or pill, in a holder therefor, and in providing air admission means, between the pill and its holder, to supply the necessary oxygen for co-action with the alcoholic vapors in whose path the catalyst is disposed, for rendering said catalyst incandescent.

Other features and advantages of my invention will hereinafter appear.

In the drawing:

Figure 1 is a sectional elevation of my improved lighter.

Fig. 2 is a section on the line 2—2 of Fig. 1.

Fig. 3 is a section on the line 3—3 of Fig. 1.

Fig. 4 is a partial, sectional elevation showing a modified form of my improved lighter.

Fig. 5 is a top plan view of Fig. 4.

Fig. 6 is a section on the line 6—6 of Fig. 4, and Fig. 7 shows a modified form of closure means.

In Figs. 1, 2 and 3, wherein my improvement is shown in one form thereof, let 1 indicate a casing, in which is disposed absorbent material 2 that is to be saturated with vaporizable fuel, such for example as alcohol. An outer shell 3 is also shown as adapted to ensheathe the lower closed portion of casing 1, and a removable cover 4 is shown as adapted to fit over the upper, open portion of said casing, an annular bead 5 upon the casing serving as a stop both for the shell 3 and cover 4.

Removably fitting the upper, open end of casing 1 is a holder 6, here shown as a tubular member, here represented as having a reduced portion 7 adapted to enter and frictionally engage the casing at the upper end thereof, and the main portion of said holder, whose outside diameter may be the same as that of casing 1, having a shoulder 8 that abuts against the casing edge to limit the extent of entry by said holder into the casing.

The holder 6 is intended to support the catalyst in the path of vapor leaving the absorbent material 2, and said catalyst, which is in the form of a disk 9, of spongy platinum or platinum black, and may have an aperture 10 therethrough, is suitably supported in the holder, and is retained therein at the forward end by means of inwardly angled tongues 11, struck from the material of the holder at its outer end, said tongues lying against the outer surface of disk 9.

The supporting means for disk 9 here shown

comprises a socket member having the perforated base 12 and surrounding wall 13, said wall being provided with peripheral protuberances 14 that are intended to engage frictionally with the inner surface of holder 6, to thereby lodge said socket within the holder, and to space the socket, and hence the disk 9 away from the holder wall, thereby providing a clearance 15 between said socket and holder for the passage of air to the holder interior, so that vapor from the fluid 10 with which the absorbent material is charged may co-act with the catalyst in the presence of air.

The clearances between succeeding tongues 11 permit the passage of air to clearance 15.

It will be apparent that upon applying a cigarette end to the disk 9, and drawing upon the cigarette, through aperture 10, air is induced to flow through the clearances between tongues 11 and through clearance 15, into the holder interior, for the purpose set forth.

In order to prevent fuel vapors from condensing and thus wetting the catalyst when the cap is in place, I may, as shown in Fig. 7, cause the crown A of cap 4 to lie closely upon the disk 9, instead of, as in Fig. 1, leaving a space between the disk and the cap, which space, in the course of time, would permit fuel vapor to collect therein and condense upon the disk. When the catalytic disk bears condensed vapor it becomes necessary to first subject the disk to heat, to dry it out, before the desired reaction can occur. Therefore it is my purpose by this improvement, to close the cap down upon the catalyst, so that substantially no space may be left between these elements for entrapping vapor charged air. By avoiding the provision above the catalytic disc of such a space of any substantial extent as far as is practicably possible, the opportunity for fuel vapors to be present thereabove in position to condense thereon is reduced to a practical minimum.

In the modification of Figs. 4, 5 and 6, the same instrumentalities are employed as in the preceding figures, excepting that in this instance the socket wall 13 is extended up beyond the disk 9, and has an outwardly curved flange 16, a split ring 17, that is tensioned within the holder, engaging beneath the flange to thus support the socket; said wall extension being provided with apertures 18, that are located below ring 17, for communicating air to the clearance 15 and thence to the holder interior.

Variations within the spirit and scope of my

55

invention are equally comprehended by the foregoing disclosure.

I claim:-

1. A cigarette lighter having a casing adapted to contain a vaporizable fuel, said casing including a hollow holder portion, a catalytic element disposed in said holder portion in the path of vapor from said fuel and having a face exposed for cooperation with the end of a cigarette or the like, said element being peripherally spaced from said holder portion to provide a clearance for the passage of air to the casing interior, said element also being bodily pervious to the passage of air, and means for supporting said element in said holder.

2. A lighter having a casing adapted to contain a vaporizable fuel, said casing including a hollow holder portion, a catalytic element disposed in said holder portion in the path of vapor from said fuel, said element being peripherally spaced from said holder portion to provide a clearance for the passage of air to the casing interior, means for supporting said element in said position, and tongues inwardly angled from said holder portion to engage said element and retain it in said supporting means.

3. In a lighter having a casing and absorbent material therein to be charged with vaporizable fuel, a hollow holder to fit said casing, a catalytic element disposed in said holder in the path of vapor from said fuel, said element being peripherally spaced from said holder to provide a clearance for the passage of air to the holder interior, means for supporting said element from said holder, and spaced tongues inwardly angled from said holder to engage said element and retain it in said holder, the spaces between said tongues permitting air to pass to said peripheral clearance.

4. In a lighter having a casing and absorbent material therein to be charged with vaporizable fuel, a hollow holder to fit said casing, a catalytic element disposed in the path of vapor from said fuel, supporting means for said element, said supporting means being provided with a plurality of spaced protuberances adapted frictionally to engage the interior of said holder to hold said supporting means in peripherally spaced relation therewith and provide a clearance for the passage of air into the casing interior, the body of said catalytic element being pervious to air and fuel vapor.

5. In a lighter having a casing and absorbent material therein to be charged with vaporizable fuel, a hollow holder to fit said casing, a catalytic element disposed in the path of vapor from said fuel, means within said holder for supporting said element therein in peripherally spaced relation therewith, to provide a clearance for the passage of air to the holder interior, tongues angled inwardly from said holder to retainingly engage said element at its exposed surface, and a cap to removably fit said casing, said cap, when fully seated, presenting its crown in close proximity to said element to prevent the formation of vapor condensation upon the element.

6. A lighter having a casing adapted to contain a vaporizable fuel, a catalytic element supported at one end of said casing in the path of vapor from said fuel and having a face exposed for cooperation with the end of a cigarette or the like, means for allowing circulation of air into said casing and past said element, and a removable cap for said casing adapted to seat snugly adjacent said exposed face of the element with substantially no air space between the cap and said face.

GEORGE PHILIP SCHMITT.
